UNITED STATES PATENT OFFICE

SAMUEL E. HITT, OF ELYRIA, OHIO

HULL UNIT FOR AIR AND WATER CRAFT

Application filed April 8, 1930. Serial No. 442,576.

This application is a partial continuation of my application No. 264,634, filed March 26th, 1928 and relates to important elements of construction for hull units and superstructures, such as were disclosed in my said application, together with other important improvements.

More particularly, my invention relates to the construction of the hull, to make it seaworthy even in rough weather and to provide it with reserve buoyancy in case the hull proper becomes damaged and is unable to carry the load.

My two hull aero-plane-ship is primarily and aero-hydro-glider, capable of carrying a thousand passengers or more and of making from one hundred and forty to two hundred miles an hour when skipping over the tops of waves or barely touching smooth water.

My aero-plane-ship (hereinafter called aeroship) is approximately a thousand feet long and weighs several hundred tons and is built to clear the water at maximum speed but not intended to ever rise more than a few feet above the water as will be explained further on.

Many attempts have been made to fly across the Atlantic and Pacific Oceans with a few marked achievements and numerous disastrous failures and my invention is intended to overcome the difficulties of such a long flight for areoplanes, by utilizing the sustaining value of the water and by certain novel features of construction as will enable my aeroship, to safely ride out a storm.

On the Atlantic Ocean the wind sometimes attains a velocity of about eighty miles an hour with waves averaging over thirty feet high.

These waves not only travel fast but have been known to have a span of eight hundred feet from crest to crest of waves.

When all is well, my aeroship can safely fly through such a storm, but if things go wrong, and several of the propellers get out of commission or the aeroship loses several of its aeroplanes, it may be necessary to slow down and settle on the water to ride out the storm.

In this case my aeroship is subjected to the

supreme test. The hulls are of small cross section in comparison to their great length and would not of themselves be seaworthy.

Even in rough weather when the waves are running fifteen or twenty feet high, the sea is sometimes traversed by huge swells from thirty to forty feet high, superimposed on the other waves and traveling perhaps in a different direction. In case my aeroship was riding out a storm and encountered such high swells and the hull buckled under the strain, causing my aeroship to list or subside and to draw more water, the lives of passengers and crew would be imperiled.

An object of my invention therefore is to reinforce the hull with a bridge like structure of such height and width as will make the hull strong enough to withstand the excessive strains when the hull spans from crest to crest of long waves and to withstand side strains due to pounding of the waves when the aeroship is not headed in the direction of wave travel.

Another object of my invention is to provide a series of auxiliary floats several feet above the hull, so that in a rough sea, when the hull is deeply immersed in the high waves, the floats will skip through the tops of waves and prevent the hull from further immersion.

Another object of my invention is to provide a series of safety floats at a higher level at the bow and stern to prevent my aeroship from diving into a swell, with perhaps disastrous results.

The present day liner is high at the bow with little danger of waves washing the upper deck. In my aeroship, no such large hull surfaces are permissible, as the air resistance at high speeds would be prohibitive.

Another object of my invention therefore is to provide the bow and stern with additional safety floats at still higher levels, constructed to offer very little resistance to air currents, i. e. the wind or air currents due to travel.

Another object of my invention is to reduce head resistance to water of my auxiliary floats by constructing the lower series of floats with cylindrical cross sections instead

of the ovaloid sections used in the series of floats above.

Another object of my invention is to provide my hull with longitudinal and transverse web plates for the purpose of making the hull more rigid and also for the purpose of providing a cellular construction so that in case of mishap, the damage will be localized and most of the hull will remain intact.

Another object of my invention is to provide such longitudinal web members so disposed within the hull as to be in line with the central and side loading planes of the intermediate framing.

Another object of my invention is to so dispose the transverse web members within the hull that one such web will be located at every panel point of the intermediate framing.

Referring to the drawings:—

Fig. 1 is a plan of my hull unit.

Fig. 2 is a side elevation of the same.

Fig. 3 is a sectional plan on line 3—3 of Fig. 2.

Fig. 4 is a front elevation.

Fig. 5 is a part plan of hull with top plate removed.

Fig. 6 is a part section of hull on line 6—6 of Fig. 5.

Fig. 7 is a cross section of hull on line 7—7 of Fig. 6.

Fig. 8 is a cross section of a frame member.

Fig. 9 is a cross section of another frame member.

Numerals 1 is a hull supporting the main frame 2 through the intermediate framing 3.

In my aeroship as now planned, the hull 1 is 20 feet wide and 20 feet deep, the main frame or bridge member 2 is 40 feet square and a thousand feet long, carried by the intermediate framing 30 feet above the hull 1.

In smooth water, the weight of my aeroship with its load causes the hull to draw about twelve feet of water or half of its volume as shown by the water line 10—10.

When the sea is rough and the waves are running high as indicated by the broken line 11—11, long stretches of the hull will be out of the water as from *a* to *b* and from *c* to *d* and other parts as from *b* to *c* will be entirely submerged.

I therefore provide auxiliary floats 4 a few feet above the hull 1 to add buoyancy when the waves are high enough to reach them, to prevent the hulls from sinking much further in the water. The floats 4 are of cylindrical form to reduce both air and water resistance.

Should my aeroship encounter a huge swell such as indicated by the broken line 12—12, then longer stretches of hull 1 will be out of the water as from *m* to *n* and more of the framing will be immersed.

To meet such a condition and to prevent the waves from ever reaching the lower

cabins 5, I provide a second series of auxiliary floats 6 and 6' along the bottom line of the main frame or bridge 2 or lower deck level.

When one of these huge swells is encountered, the greatest shock will be caused by the first impact, either fore or aft as the case may be.

I therefore provide additional safety floats 7 and 8 at higher levels at both the bow and stern to prevent my aeroship from diving or getting swamped and to cause the aeroship to ride up on the wave 12—12.

The end float 6 and the safety floats 7 and 8 are arranged pyramid like to follow the contour of the wave 12—12.

The hull 1 with the auxiliary floats 4 and 6 and the safety floats 7 and 8 form a laminated hull to provide a graduated buoyancy under varying conditions of travel without offering any unnecessary resistance to either air or water.

On the second float level, i. e., for the upper auxiliary floats, the end floats 6 extend across the main frame 2 on account of the bow construction and the objective of getting a large volume at this level forward and aft of the cross bridges shown in my application No. 264,634 filed March 26th, 1928, and connected to the main frame 2 at 25 and 26.

The auxiliary floats 6' at this second series level, intermediate between the end floats 6 are placed in pairs on each side of the frame 2 as shown, partly for better construction but principally to allow for passage of water in case the waves should reach them, thus reducing water resistance and pounding.

In Fig. 8 is shown a frame member of triangular form 15, and in Fig. 9 is shown a double triangular section 16 or diamond with central web 17.

The section can be used in several ways but preferably with the apex 9 turned toward the resistance of external forces, either air or water.

All members of the main frame 2 and intermediate framing 3 are made with either section 15 or section 16 as far as practicable.

The load to be carried by my hull 1 and main frame 2 consists of not only their own weight, but the weight of the masts 20, aeroplanes 21, propeller units 22, cabins 5 and 23, the load due to the cross bridges 25 and 26 and other apparatus and machinery mounted on the main frame.

The main frame 2, or bridge member, is made strong enough to carry the above load over exposed spans between supporting waves referred to above and the hull 1 and intermediate framing 3 add further strength, the three elements acting together as a compound beam, considered as doubly safe.

In order to attain speeds of 140 miles per hour or more, it is necessary to reduce the head resistance of hull to water and the skin resistance of hull to water to a minimum.

In other words, for the power available and the lift of the aeroplanes, the aeroship must be as light as possible so that the hull 1 will draw a minimum depth of water.

5 I therefore plan to construct my entire unit, the hull 1, main frame 2, intermediate framing 3, cabins 5 and 23, with their bracket framing 24, of aluminum bronze.

The reason for desiring a speed of over a 10 hundred miles an hour is that when a storm area approaches, the pilot can change his course and run away from the storm. With a speed of over one hundred miles an hour, my aeroship can be placed in regular trans- 15

Atlantic service.

As shown in Figs. 5, 6 and 7, hull 1 has a smooth cylindrical bottom 30, sloping sides 31 and top plate 32 of considerable curvature to more readily drain off the wash.

20 The sides 31 are inclined from the vertical to be in line of strain from the framing 3 and also for the purpose of increasing the buoyancy rapidly as the hull 1 becomes further immersed in the water.

25 Hull 1 is provided with a central web 33, webs 34 at right angles to webs 31 and webs 35 from center to gunwales, dividing the hull section into six parts of about equal area. With the cross webs 36, the hull is thus divided into a great number of air tight and 30 water tight cells or compartments, making the hull practically non-sinkable.

In brief my invention consists of a long 35 cellular hull reinforced by a main frame or bridge which carries the loads due to floats, cross bridges, cabins, masts, aeroplanes and other apparatus, the hull having sufficient buoyance to carry the above loads under normal conditions and the main frame or hull 40 bridge member having sufficient strength to resist all longitudinal, horizontal and vertical strains due to air or water or loading, auxiliary floats to add buoyancy to the hull in rough weather when the waves run high, 45 and additional safety floats at higher levels to prevent the bow from diving or the stern from being swamped when a high swell is encountered.

I claim:

50 1. In an air and water craft, a hull of relatively small cross-section in proportion to its length, a main structural metal frame-work secured to the said hull and extending above the said hull for the entire length of the hull, the said frame-work including a plurality of upright cross-bracing portions spaced from each other longitudinally of the hull.

55 2. In an air and water craft, a hull, a structural metal upper framing extending above the hull and wider than the hull, an upwardly widening intermediate framing interposed between the hull and the said upper framing for supporting the latter from the hull, and a 60 plurality of sets of floats extending across

the upper framing at relatively different levels.

3. In an air and water craft, an assemblage of elements as per claim 2, in which the number of levels at which floats are disposed adjacent to the bow and the stern of the craft is greater than at which floats are disposed in the intermediate portions of the craft.

4. In an air and water craft, a hull of relatively small cross-section in proportion to its length, a main structural frame-work secured to the said hull and extending above the said hull for the entire length of the hull, and wing carrying masts spaced longitudinally of and supported by the said main frame-work, the said frame-work being of a general transverse section widening upwardly from the hull and thereafter rectangular.

5. In an air and water craft, a hull of relatively small cross-section in proportion to its length, a main structural frame-work secured to the said hull and extending above the said hull for the entire length of the hull; wing carrying masts spaced longitudinally of and supported by the said main frame-work; and air moving propeller units supported at opposite sides of the base portions of the masts and laterally outward of the upper portion of the said main frame-work.

6. In an air and water craft, a hull of relatively small cross-section in proportion to its length, a main structural frame-work secured to the said hull and extending above the said hull for the entire length of the hull, wing carrying masts spaced longitudinally of and supported by the said main frame-work, the said frame-work of a general transverse section widening upwardly from the hull and thereafter rectangular; two auxiliary frame-works extending along opposite sides of the said rectangular portion of the main frame-work; and cabins supported by each of the said auxiliary frame-works.

7. In an air and water craft, a hull of relatively small cross-section in proportion to its length, a main structural frame-work secured to the said hull and extending above the said hull for the entire length of the hull, wing carrying masts spaced longitudinally of and supported by the said frame-work, the said frame-work being of a general transverse section widening upwardly from the hull and thereafter rectangular; two auxiliary frame-works extending along opposite sides of the said rectangular portion of the main frame-work; and cabins supported by each of the said auxiliary frame-works, the cabins at each side of the craft being disposed within the confines of the auxiliary frame-work at that side of the craft.

8. In an air and water craft, a hull, a structural upper frame-work extending above the hull and wider than the hull, an upwardly widening intermediate frame-work interposed between the hull and the said upper

frame-work for supporting the said upper framing from the hull, a plurality of groups of floats supported above the hull by the said frame-work, the floats of each group being symmetrically disposed with respect to the longitudinal and vertical medial plane of the hull, each group of floats being at a different level and extending for substantially the full length of the hull.

10. 9. In an air and water craft, a hull, frame-work and float assemblage as per claim 8, and auxiliary groups of floats supported by the framing above the uppermost of the aforesaid groups of floats respectively at the bow and the stern of the craft.
15. 10. In an air and water craft, a hull, frame-work and float assemblage as per claim 8, and cabins supported by the upper frame-work at a level intermediate of the levels of two groups of floats.

20. Signed at Elyria, in the county of Lorain and State of Ohio, this fourth day of April, 1930.

SAMUEL E. HITT.
